UNITED STATES PATENT OFFICE.

JOHN P. EUSTIS, OF NEWTON, MASSACHUSETTS.

DESIGN FOR A MIRROR OR PICTURE FRAME.

No. 39,641.

Specification for Design.

Patented Oct. 27, 1908.

Application filed July 6, 1908. Serial No. 442,265. Term of patent 14 years.

To all whom it may concern:

Be it known that I, JOHN P. EUSTIS, a citizen of the United States of America, residing at Newton, in the county of Middlesex and State of Massachusetts, have invented a new, original, and ornamental Design for Mirror or Picture Frames, of which the following is a specification, reference being had to the accompanying drawings, forming part thereof, and in which—

Figure 1 is a plan, and Fig. 2 is a side elevation of the frame.

The design comprises an oblong face *a*, an oblong side surface *b*, an oblong outwardly curved rim *c*, and round corners *d*. A beading *e* is located at the juncture of the oblong face *a* and the oblong side surface *b*.

I claim—

The ornamental design for a mirror or picture frame, substantially as shown.

JOHN P. EUSTIS.
